DESIGN FOR A COIN CHUTE MOUNTING PLATE

Bernhard C. Grunig, Chicago, Ill.

Application September 20, 1937, Serial No. 71,693

Term of patent 7 years

To all whom it may concern:

Be it known that I, Bernhard C. Grunig, a citizen of the United States and a resident of Chicago, in the county of Cook and State of Illinois, have invented a new, original, and ornamental Design for a Coin Chute Mounting Plate, of which the following is a specification, reference being had to the accompanying drawing, forming a part thereof, and in which:

Fig. 1 is a front side perspective view of the new design for a coin chute mounting plate as seen from above;

Fig. 2 is a top plan view of the new design for a coin chute mounting plate; and

Fig. 3 is a bottom plan view of the same.

I claim:

The ornamental design for a coin chute mounting plate, as shown.

BERNHARD C. GRUNIG.
